UNITED STATES PATENT OFFICE.

FRANK C. FOSDICK, OF CHICAGO, ILLINOIS.

MECHANICAL STOKER.

1,089,697.

Specification of Letters Patent. Patented Mar. 10, 1914.

Application filed October 18, 1912. Serial No. 726,462.

To all whom it may concern:

Be it known that I, FRANK C. FOSDICK, a citizen of the United States, and residing at Chicago, in the county of Cook and State of Illinois, have invented certain new and useful Improvements in Mechanical Stokers, of which the following is a specification.

This invention relates to mechanical stokers adapted to feed fuel into furnaces; and it is particularly adapted to handle coal of all grades of coarseness, and to distribute the coal upon the grate so as to feed the fire in the most efficient manner.

It has been found in the use of mechanical stokers that difficulty arises in properly distributing the coal. The tendency of the ordinary stoker is to deliver more coal at some particular places upon the grate than is required, and to deliver too small an amount of coal in other places. As a consequence, portions of the bed of coal receive too little air and other portions receive too much, fuel being thereby wasted and the capacity of the furnace materially reduced.

One of the objects of this invention is to provide means for overcoming these difficulties. This result is brought about by the use of a fuel-transporting conduit which projects into the furnace and which is provided with manual means whereby the fuel-outlet opening of the conduit may be changed in position and direction so that the distribution of the fuel is at all times under the full control of the fireman.

It has also been found that in the use of mechanical stokers the draft is more or less interfered with by the stoker. To avoid this I have provided a stoker so constructed that the passageways through which the fuel passes are closed or substantially closed during the time when the stoker is in operation, and so that the conduit through which the fuel passes into the fire-place is entirely closed when the stoker is not in operation.

It has also been found that the intense heat of the fire tends to injure the portions of the stoker which project into the furnace; and this is particularly so with a stoker which is adapted to project a substantial distance into the furnace in order to distribute the fuel properly. To prevent this I have provided means whereby the more sensitive portions of the projecting end of the stoker may be withdrawn, when the stoker is not in use, sufficiently so as to prevent danger of

injury; and as a further precaution in this regard I have provided means for closing the fuel outlet, when the stoker is not in use, thereby preventing the heat from reaching the portions of the stoker which are likely to be injured thereby.

Another object of the invention is to provide means for imparting sufficient kinetic energy to the fuel to cause it to pass at high speed through the fuel conduit into the fire-place, and thus to pass out of the conduit into the fire-place under its own momentum, and in this way to be forced, under the control of the operator, to the portion of the fire-place where needed. It has been found that this method of feeding and distributing allows fuel of any reasonable degree of coarseness to be used and distributed where desired. It is immaterial what the size of the piece of coal may be; it will be carried by its momentum through the conduit and to the point desired, as the distance which such a moving mass will travel depends on its speed and not on its size. As a consequence the small particles and large masses of coal are uniformly distributed throughout the fire-place; while, as is well known, stokers using other methods for delivering the fuel tend to segregate the smaller particles from the larger, thereby distributing the fuel inefficiently.

A further object of the invention is to provide a mechanical stoker which is especially adapted for use upon locomotives; which shall be applicable to existing locomotives without requiring any alteration of the furnace; and which shall be capable of being quickly disconnected from the furnace and moved aside in case hand-stoking becomes necessary or desirable.

In the accompanying drawings, Figure 1 is a side elevation of a mechanical stoker which embodies the features of my invention. Fig. 2 is a plan view of the stoker. Fig. 3 is a vertical transverse section of the stoker along the lines 3 3 3 of Fig. 1. Fig. 4 is a vertical transverse section of the stoker along the lines 4 4 of Fig. 1. Fig. 5 is a vertical longitudinal section of the fire-place end of the stoker conduit. Fig. 6 is a horizontal longitudinal section of the forward portion of the stoker conduit delivering fuel. Fig. 7 is a plan view of the fire-place end of the conduit delivering fuel.

The stoker comprises in general a hopper

for receiving the coal and passing it into the center chamber of a rotating cylinder. The cylinder is inclosed by a cylindrical casing, the inner surface of which is adjacent to the outer surface of the rotating cylinder. The cylinder has a passageway from its central chamber to its outer surface, through which the fuel is forced by the centrifugal action of the rotating cylinder; and it is thus forced at high speed through an opening in the casing into a horizontal conduit and through the conduit into the combustion chamber. The conduit, which projects into the furnace, may be extended a greater or lesser distance therein, and the path of motion of the fuel therethrough may be varied, so that the fuel may be forced to pass out of the conduit in any direction desired and thus be distributed where needed.

The fuel is placed in the hopper 10 by any suitable means and at any convenient time, and rests upon a slide 11 in the lower part of the hopper. When it is desired to feed fuel into the furnace the slide 11 is withdrawn by some suitable means such as the slide handle 12, and coal is allowed to flow for the desired length of time into the hopper passageway 13 and into the central chamber of the cylinder 14. This cylinder is mounted on ball-bearings 15 in the cylindrical casing 16 and is free to rotate therein. Connecting the central portion of the cylinder with the exterior is a passageway, the outer end of which is open and moves adjacent to the inner surface of the cylindrical casing 16 as the cylinder rotates.

The cylinder may be rotated by any suitable means. Herein I have shown a two-cylinder steam engine 18 which is adapted to operate a shaft 19; and thus, by means of connecting gearing, rotate the cylinder in the direction and at the speed desired. The supply of steam to the engine 18 is controlled by a foot-operable valve 18^a. This valve may be detachably connected to a pipe supplying steam from the locomotive boiler.

Near the upper surface of the casing 16 is an opening 20, and tangentially connected to the casing is a tube 21. The tube 21 is the rear end of a fuel-transporting conduit 22 which is mounted horizontally on the frame 23, and which connects the opening 20 of the casing 16 with the furnace 23^a. This conduit comprises two tubes 21 and 24, an extensible false bottom 25, and extensible false sides 26. Portions of the vertical sides of the tube 24 are cut away and the openings closed by inner plates 24^a rigidly attached to said tube. In practice, the tube 24 extends to a point within the furnace door-way. On each side of the tube 24 are plates 24^b to close the spaces between the sides of the tube 24 and the sides of the doorway. The space above the tube 24 is

closed by a door 24^c hinged to the furnace door frame. The tubes 21 and 24 are at all times stationary with reference to the stoker as a whole. But the bottom 25 and sides 26 are slidably mounted between the walls 70 of the two tubes and are adapted to be slid forward a substantial distance into the furnace.

Any suitable means may be provided for sliding the false bottom and sides forward 75 and backward. The means which I have provided for the purpose comprises a fluid pressure cylinder 27 inclosing a piston, the piston rod 28 of which is connected to a lug 29 projecting downwardly from the bottom 25. The piston within the cylinder may be forced to either end of the cylinder by passing steam or other gas under pressure into the proper end of the cylinder through the valve 29^a. When, for instance, steam is admitted into the right-hand end of the cylinder the piston is forced toward the left and the false bottom is slid forward into operative position in the furnace. When the bottom is thus moved forward it moves with 90 it the false sides. The means which I have provided to accomplish this are the following: At the forward end of the false bottom is pivoted a horizontal disk 31, the upper surface of which is approximately flush 95 with the upper surface of the false bottom (as shown in Fig. 5) and the lower surface of which is approximately flush with the lower edges of the false sides. Extending around this disk and connecting the lower edges of the false sides is a series of hinged sections forming a chain 32. When the false bottom is slid forward, this chain is forced forward by the disk, and the sides are drawn forward by the chain. At the end of the 105 false bottom is an arcuate flange 31^a, which with the disk 31 forms a groove within which the chain lies. As the bottom is moved backward this flange pushes backward the chain and the false sides. So that the sides 110 always move with the bottom.

When the bottom and sides have been moved forward in operating position, in order to distribute the fuel to all points upon the grate it is desirable to vary the direction at which the fuel passes out of the end of the conduit. I have provided the following means for this purpose: On the upper side of the conduit on each side, and fixed to a flange or rib 26^a on the false side 115 by means of the bolts 33, is a toothed rack 34 (Fig. 4) which is adapted to slide with the false side along the guide 35. A slot 34^a is formed in the plate 24^a and the tube 24, at each side of the conduit, to accommodate 120 the movement of the ribs 26^a. A plate 36 is slidably mounted upon the tube 24, between the racks 34, and pivoted to this plate is a gear wheel 37 which meshes with each of the racks. An arm 38 is fixed to and adapt- 130

ed to rotate the gear wheel 37. When the wheel, by means of this arm, is rotated, the rack and false side at one side of the conduit are slid forward and the rack and false side on the other side are slid backward. The forward ends of the false sides 26 are flexible, being composed of hinged sections 30; and when a false side 26 is moved forward, its forward portion is flexed or bent 5 around the disk 31, as indicated in Fig. 6. In this manner the forward end of either side may be curved around the disk, and the direction of the outlet of the conduit may be thus varied at the will of the operator. The extreme forward end of each side 26 consists of a section 30^a which is longer than the sections composing the flexible side walls 30. When one of the sides 26 is advanced into the position shown in Fig. 10 6, the section 30^a of that side extends at a right angle to the conduit, and assists to guide the stream of coal in making a right-angular change of direction. Pivoted to each of the vertical sides of the fixed tube 24 is a wing 39, which is adapted to be 15 swung inwardly so as to vary the path of the fuel through the conduit. Normally the wing lies against the side of the tube. On the free end of the wing is a cam surface 40 extending outwardly from the side of the tube. As the false side is drawn away from 20 the furnace, a cam or wedge 41 on said side is brought in contact with the cam end 40, thus forcing the wing inwardly, as indicated 25 in Fig. 6. In this manner the path of the fuel is moved toward the other side of the conduit for the purpose hereinafter mentioned.

The forward end of the tube 24 extends 30 beyond the end of the false bottom and sides when they are withdrawn outwardly, and a door 42, horizontally hinged to the upper side of the tube 24, is adapted to close the end of the conduit when the false bottom 35 and sides are thus withdrawn. When, however, the bottom and sides are forced forward they come in contact with the door and force the door open, as indicated in Fig. 5. By this means the conduit is closed 40 when not in operation so as to prevent any draft entering the furnace through the conduit and to prevent heat from the fire from injuring the movable portions of the conduit. If desired, the door 42 may be weighted, as shown, so that a draft shall not cause 45 the door to swing open.

The casing 16 and the framework 23 are rigidly connected in a suitable way, as by connecting pieces 44, and may be mounted 50 on rollers 45 so that the stoker may, if desired, be moved back to permit of hand-firing.

In practice the operation of the stoker is as follows: The hopper 10 is maintained 55 more or less full of coal, and the engine 18

is preferably kept running continuously. When it is desired to feed the fire, the speed of the engine is increased, the valve 29^a is operated to advance the false bottom 25 and sides 26, the slide 11 is pulled outwardly, 70 coal passes into the central chamber of the rotating cylinder 14, and the fuel is forced outwardly through the passageway 17. As the outer opening of the passageway 17 registers with the opening 20 to the conduit, 75 the fuel, by centrifugal action, is forced into the conduit, the backward inclination of the passageway assisting in this process, the rear wall 43 driving the fuel with a high speed forward through the conduit. If it 80 is desired to throw the fuel into the right-hand side of the combustion chamber, the gear wheel 37 is rotated as indicated in Fig. 6, and the fuel passes through the opening 44 toward the right. In the backward 85 movement of the right-hand false side the right-hand wing 39 is forced inwardly, thus forcing the fuel toward the left-hand side and causing it to pass outwardly through the opening 44 less obstructed by the end 90 section 30^a of the left-hand false side than would be the case if the fuel passed straight through the conduit and struck squarely against the section 30^a. By rotating the gear wheel 37 the outlet 44 may be shifted 95 toward the front end of the conduit, and, if desired, straight forward and toward the left so as to distribute the fuel evenly upon the grate, it being understood that fuel passes out of the outlet 44 with sufficient 100 speed to carry portions of it to the most remote points of the grate. When sufficient coal has been discharged into the furnace, the slide 11 is closed, and after the cylinder 14 has discharged all the coal supplied to 105 it the engine 18 may be slowed down.

By keeping the engine always in operation, the cylinder 14 may be quickly speeded up to the desired rate of rotation when fuel is to be supplied to the fire. 110

The fireman may observe the condition of the fire at any time upon raising the door 24^a.

It will be noted that the apparatus is self-contained, requires no reconstruction of the furnace, is at all times under the control of the fireman, is not subject to injury by the heat of the combustion chamber, and is of such size and character that it may be supported upon the deck of the locomotive without inconvenience to the engineman. 115

Although I have shown by the drawings and described herein specific mechanism throughout for the purpose of clearness, yet it is to be understood that modifications in the structure may be made by those skilled 120 in the art without departing from the spirit of the following claims, and that the invention is not limited to locomotive furnaces.

I claim as my invention:

1. In a mechanical stoker, a fuel conduit 130

- adapted to project into a furnace, means for projecting fuel at a high speed into said conduit, means for varying the path of motion of said fuel while in said conduit, said means comprising wings pivoted to the interior sides of said conduit, and means for varying the path of motion of said fuel as it leaves said conduit, the last mentioned means being arranged to operate said wings.
10. 2. In a mechanical stoker, a fuel - transporting conduit adapted to project into a furnace, the sides of the discharge end of said conduit being slidably mounted, means for sliding one of said sides outwardly and the other of said sides inwardly, and means for turning the end of the outwardly slid side toward the other side, whereby the conduit opening may be faced in different directions.
20. 3. In a mechanical stoker, a fuel-trans- porting conduit adapted to project into a furnace, the sides of the discharge end of said conduit being slidably mounted and flexible, means for sliding one of said sides outwardly and the other of said sides inwardly, and means for flexing said outwardly slid side toward the other side, whereby the position of the conduit opening is changed.
30. 4. In a mechanical stoker, a fuel conduit adapted to project into a furnace, the sides of the discharge end of said conduit being slidably mounted, means for sliding one of said sides outwardly and the other inwardly, said means comprising a toothed rack operatively connected to each of said sides, a gear wheel meshing with each of said racks, and means for rotating said gear wheel.
5. In a mechanical stoker, a fuel conduit adapted to project into a furnace, a plurality of hinged sections in each side wall of the furnace end of said conduit, a disk pivoted at the end of said conduit and extending horizontally between said walls, the end section of each of said sides being fixed to said disk, and means for rotating said disk.
6. In a mechanical stoker, a fuel conduit adapted to project into a furnace, said conduit having a false bottom and false flexible sides, means for extending said bottom and sides beyond the outlet end of said conduit,
- and means for flexing the inner end of one of said sides toward the other side.
7. In a mechanical stoker, a fuel conduit adapted to project into a furnace, said conduit having a false bottom and false sides, means for extending said bottom and sides beyond the outlet end of said conduit, and means for moving one of said sides backward and the other forward.
8. In a mechanical stoker, a fuel conduit, means for passing fuel into one end of said conduit, means for closing the other end of said conduit, said conduit having a false bottom and false flexible sides, means for extending said false bottom and sides so as to open and to project beyond said other end, means for flexing the inner end of one of said sides toward the other side.
9. In a mechanical stoker, a fuel - trans- porting conduit adapted to project into a furnace, the sides of said conduit being flexible, means for sliding one side inwardly, and means for flexing the inner end of said side toward the other side.
10. In a mechanical stoker, a fuel-trans- porting conduit adapted to project into a furnace, the sides of said conduit being flexible, means for sliding one side inwardly, and means for flexing the inner end of said side toward the other side, said flexing means comprising a wheel rotatably mounted in the bottom of the discharge end of said conduit, and a chain passing around said wheel and connected to the inner ends of said sides.
11. In a mechanical stoker, a fuel conduit adapted to project into a furnace, the sides of the discharge end of said conduit being slidably mounted, means for sliding one of said sides outwardly and the other inwardly, said means comprising a toothed rack operatively connected to each of said sides, and a gear wheel meshing with each of said racks, said wheel and racks being positioned on the top of said conduit.

In testimony whereof I affix my signature in the presence of two witnesses.
